UNITED STATES PATENT OFFICE.

LUDWIG LIEDLER, OF MODLING, NEAR VIENNA, AUSTRIA.

APPARATUS FOR USE IN ERECTING WALLS OF BLOCKS, BRICKS, OR THE LIKE.

Application filed August 8, 1925, Serial No. 49,058, and in Austria July 12, 1924.

This invention relates to an apparatus for use in erecting walls from stone blocks with the aid of vertically adjustable guide laths or ledges as stops or guides for the blocks, and is constituted by a template enclosing the whole masonry in its plan or cross-section, both at the longitudinal sides and at the transverse sides. This template forms the guide for the stone blocks as well as the casting mould for the rough plastering, and can be pulled upwards or raised each time to the height of a layer of blocks. Another feature of the invention is the special shape of the template as well as the connection of template to a well known scaffolding or frame forming the stand for the mason, which frame is pulled upwards simultaneously with the template. The invention substantially differs from similar well known arrangements in enabling masonry of any desired cross-section to be erected as the template is adapted already before starting the work, to all projecting and re-entering corners of the masonry and of the piers, and in that shape is used until the next offset is reached which is of smaller wall thickness. At this level the template is adapted to the new thickness of wall, and in this shape pulled up again layer by layer until the next level. Moreover the apparatus according to the invention differs from the well known constructions also by the fact that the template forms the well known guide or stop for the blocks, and at the same time a casting mould for the rough plastering.

A construction of the apparatus according to the invention is illustrated by way of example in the accompanying drawing in which

Figure 1 is a perspective view of the template in use during building,

Figure 2 is an enlarged view of a part of the template,

Figure 3 shows the apparatus in elevation,

Figure 4 is a plan, and

Figures 5 and 6 show a mortar tank and mortar truck.

The template *s* shown in perspective in Figure 1, is made, to suit the cross-section of the masonry, from single laths which are secured together by nails, clips, brackets or the like. At suitable distances apart levelled uprights *t* are arranged with spaced markings on which the template is guided by suitable sleeves *u* or the like. The template

s is provided at its upper edge facing the masonry, with guide ledges *r* which form guides for the blocks, and several distance ledges *l* are arranged at suitable distances apart to engage directly with the front faces of the blocks already set. The height of the template *s* is greater than that of a layer of blocks, for instance it is equal to three times the height of the layer. The distance of the inner faces and of the guide ledges *r* as well as of the distance ledges *l*, from the template, corresponds to the thickness of the rough plastering. For the purpose of facilitating the work, the template *s*, and a scaffolding *g* constituting the stand for the mason, can be simultaneously moved upwards, as shown in Figures 3 and 4. The scaffolding *g* is provided above the template *s* with a material supporting board, not shown in the drawing, and is guided at intervals of several meters for instance by rollers *o* on an upright *n* and carries jibs *a* to which the templates *s* are suspended. For the purpose of improving the supporting of the templates, a shackle or bracket *b* surrounds the upright *n* and is longitudinally adjustable thereon. On the upper cross beam *q* of the framework *k* supporting the upright *n*, for instance a rope pulley *i* is mounted on which the scaffolding *g* together with the templates *s* can be raised by means of a hand wheel *h*. The templates *s* are preferably easily detachable from the frame or scaffolding *g* at *x* and can be raised also independently of the scaffolding *g* so that at the beginning of the work, only the templates need be pulled upwards layer by layer, and the coupling to the scaffolding frame is effected only when the progress of the masonry work necessitates an increase in the height of the stand for the workman. The upper edges of the template are preferably used as rails for a mortar truck *w*, on the back of which is provided a stripping off device for the mortar coming from the mortar trough *m*. The mortar trough *m* is provided at its lowest point with a hinged flap valve *v* which closes an outlet slot and is turned outwards when it is desired to use the mortar, with simultaneous movement of the trough *w* from the position shown in Figure 5.

The working of the apparatus is as follows:

The first two layers of stone blocks are laid in accordance with the desired cross

section, then the supporting frames *k* are erected, and the templates mounted round the cross-section and secured to the supporting construction. The front edges of the distance ledges *l* are then situated at the front faces of the first layer, whilst the inner faces of the template boards are further outwards to the extent of the height of the ledges *r*, *l*. The uprights *t* are then put in and levelled, whereupon the masonry work can begin. The blocks of the next layer are then placed against the guide ledges *r* thus eliminating the necessity of plumbing and levelling. After finishing a complete layer, the template is raised to the height of a layer, and the hollow space left below the guide ledges *r* is filled with liquid coarse mortar, whereupon the next layer of blocks is set. The time required for setting the next layer is sufficient to give the coarse plastering time for setting or binding so that at the next raising and new filling of the guide ledges *r*, the lowest layer of the plaster uncovered by the raising of the template, is at the same time smoothed. The recesses in the form of grooves left free from plastering on account of the distance ledges *l* after the raising of the template, are used for checking correctness of bonding, and are covered by hand for several layers simultaneously. The distance ledges *l*, in addition to guiding the templates along the front faces of the blocks, also control the proper bonding in spite of the coarse plaster put

on. When the height of the masonry is sufficient, the frame or scaffolding *g* is also suspended at *x* to the supporting construction and subsequently raised together with the same with the template. The mortar is brought up by means of troughs *w* and levelled layerwise by means of the stripping off device *e*. At those points of the masonry where no plastering is required, the ledges *r* and *l* will of course be omitted, whereupon the blocks are placed directly against the template.

Having now particularly described and ascertained the nature of my said invention and in what manner the same is to be performed, I declare that what I claim is:

1. Apparatus for use in erecting walls of stone or like blocks and rough plaster, comprising a template entirely surrounding the horizontal cross-section of the wall being constructed longitudinally and transversely of the wall, and horizontal guide ledges mounted on the internal faces of the template to engage the blocks.

2. Apparatus for use in erecting walls of stone or like blocks and rough plaster, comprising a template entirely surrounding the horizontal cross-section of the wall being constructed longitudinally and transversely of the wall, and spaced vertical ledges mounted on the inner faces of the template to provide spaces for the reception of the rough plaster.

LUDWIG LIEDLER.
